UNITED STATES PATENT OFFICE.

DAVID F. CORKERY, OF CAMBRIDGE, MASSACHUSETTS.

DESIGN FOR A DOOR-HANGER.

SPECIFICATION forming part of Design No. 30,594, dated April 18, 1899.

Application filed March 20, 1899. Serial No. 709,861. Term of patent 7 years.

To all whom it may concern:

Be it known that I, DAVID F. CORKERY, a citizen of the United States, residing at East Cambridge, in the county of Middlesex and State of Massachusetts, have invented and produced a new and original Design for Door-Hangers, of which the following is a specification.

My invention relates to a new and original design for door-hangers, and is illustrated in the accompanying drawings, wherein—

Figure 1 is a perspective view; Fig. 2, a face view, and Fig. 3 a rear view.

The leading feature of my design consists in a door-hanger having a head or hood one face of which is of horseshoe configuration in outline, the other face of which down to the edge line of the first-named face being also of horseshoe configuration in outline, and the peripheral edge of which describes a section of a circle somewhat more than a semicircle, leaving an open space between the two faces of the hood or head.

In the said drawings the reference-numeral

1 indicates a door-hanger, one face of the head or hood 2 of which is of horseshoe configuration in outline, as shown at 3, and the other face 3^a of which down to the line of termination of the face 3 is also of horseshoe configuration in outline, as shown at 4. Below 3^a said line the face 4 continues in an extension 5. The peripheral edge of the hood or head 2 is in the form of a section of a circle somewhat more than a semicircle, as shown at 2^a.

My design presents a door-hanger of novel, pleasing, and distinguished appearance.

Having thus described my invention, what I claim is—

The design for a door-hanger herein shown and described. 40

In testimony whereof I have hereunto set my hand in presence of two subscribing witnesses.

DAVID F. CORKERY.
